RAILWAY TRUCK

Glenn F. Couch, Rochester, N. Y., assignor to
 The Symington-Gould Corporation, Rochester, N. Y., a corporation of Maryland

Application December 30, 1931, Serial No. 583,954

22 Claims. (Cl. 105—197.1)

This invention relates to railway rolling stock and, more particularly, to trucks in which the bolsters are supported by both helical and elliptic springs.

5 The principal object of my invention, generally considered, is the employment of elliptic and helical springs for supporting truck bolsters, said elliptic springs being, in some instances, arranged diagonally in order to utilize existing spring 10 planks.

Another object of my invention is an improvement in railway trucks by utilizing both elliptic and helical springs for supporting the bolsters thereof, adapter castings or plates being used to 15 underlie the bolster springs in instances where the side frames utilized do not have adequate bearing portions for the increased size of a spring group.

A further object of my invention is to provide 20 car trucks with either integral or arch bar side frames, and bolster springs involving a combination of elliptic and helical springs for securing increased capacity, lateral-motion rockers being employed, if desired, for supporting each bolster 25 above the upper spring caps of the bolster springs.

A still further object of my invention is the provision of a spring nest adapted for insertion in a bolster opening of a railway vehicle and comprising an elliptic spring and a plurality of coil 30 springs, the elliptic spring being arranged so as to extend at an oblique angle to the direction of length of the side frame with which it is associated.

Other objects and advantages of the invention 35 relating to the particular arrangement and construction of the various parts will become apparent as the description proceeds.

Referring to the drawings illustrating my invention, the scope whereof is defined by the appended claims:—

Figure 1 is a fragmentary side elevational view of a truck showing a portion of an integral or cast 40 side frame thereof with associated spring plank, bolster, nest of springs and associated parts.

45 Figure 2 is a horizontal sectional view on the line 2—2 of Figure 1, looking in the direction of the arrows.

Figure 3 is a view corresponding to Figure 2, but showing a frame of increased capacity and utilizing more helical springs than the frame of Figure 2.

50 Figure 4 is a view corresponding to Figure 1, but showing my invention embodied in a frame of the arch bar type.

Figure 5 is a horizontal sectional view on the

line 5—5 of Figure 4, looking in the direction of the arrows.

Figure 6 is a fragmentary view of the frame and spring plank on the line 6—6 of Figure 4, looking in the direction of the arrows, the associated bolster and nest of springs being shown in elevation.

Figure 7 is a fragmentary elevational view, with parts in vertical section, and corresponding to Figure 1, but showing another embodiment of my 10 invention.

Figure 8 is a fragmentary sectional view on the line 8—8 of Figure 7, a portion of the nest of springs being shown in elevation.

Figure 9 is a fragmentary sectional view on the 15 line 9—9 of Figure 7, looking in the direction of the arrows.

Figures 10, 11 and 12 are views corresponding, respectively, to Figures 7, 8 and 9, but showing my invention embodied in a frame of the arch 20 bar type.

Referring to the drawings in detail, like parts being designated by like reference characters, and first considering the embodiment of my invention illustrated in Figures 1 and 2, there is 25 shown a portion of a truck comprising a side frame 1, preferably formed of cast steel, although it will be clear that I do not wish to be limited to such construction. The frame 1 comprises a compression member 2, a tension member 3, and 30 bolster guide columns or strut portions 4 spacing intermediate portions of said compression and tension members, leaving a window opening 5 therebetween.

The tension member 3 has an upper web portion 6 extended laterally beyond the side walls 7 to provide a spring plank seat portion of adequate area. Resting on the spring plank seat 6 of the frame is one end of a spring plank 8, the other end being supported by a corresponding side frame (not shown). Any desired means may be employed for interlocking the spring plank 8 with respect to the frame 1. Resting on the spring plank and disposed in the window opening 5 of the frame is a lower spring plate or cap 9, said cap, in the present embodiment, being of a size adapted to support a four-unit nest of springs, such as employed, for example, with a fifty-ton truck.

In the present embodiment, only two helical spring units or sets 10 are employed, said spring units being arranged at opposite corners of the spring plate 9 and an elliptic spring or elliptic spring set 11 associated with said helical springs 55 and also supported on the plank. In order to

utilize existing spring planks, the elliptic spring 11 is arranged diagonally of the frame 1 and plank 8, as shown, for example, in Figure 2, thereby allowing room on each side for one helical spring unit 10 in a corner of the plate 9. If the elliptic spring 11 were disposed axially of the plank, it will be seen that said plank would have to be widened, or it would not be possible to utilize a standard helical spring on each side of the elliptic spring. An additional advantage secured by the diagonal disposition of the elliptic spring is that said spring does not extend out as far beyond the plane of the side frame 1.

Resting on the nest of springs 10, 11 is an upper plate or cap 12 which, in turn, supports the associated bolster 13. Said bolster is desirably provided with the usual guiding lugs 14 cooperating with the upper portions of the guide columns 4, as will be understood.

Referring now to the embodiment of my invention illustrated in Figure 3, a construction is there disclosed which corresponds with Figures 1 and 2, except that the frame 1^a is of greater capacity, and the spring plank 8^a and associated plate 9^a are of a size adapted to receive a six-unit nest of helical springs 10^a arranged as a regular hexagon. In the embodiment illustrated, two diagonally disposed helical spring units have been replaced by an elliptic spring 11^a diagonally disposed, as in the preceding embodiment, for similar reasons.

Referring to the embodiment of my invention illustrated in Figures 4, 5 and 6, a construction is there disclosed which corresponds to that of Figures 1 and 2, except that the frame 1^b is of the arch bar type, comprising an upper arch bar or compression member 2^b, and a lower arch bar or tension member 3^b, spaced by bolster guide columns or strut castings 4^b, held in position by through bolts 15, said bolts connecting not only the members 2^b, 3^b and 4^b, but also the tie 16.

In the present embodiment, the lower arch bar 3^b is not wide enough to form a foundation of sufficient area for the nest of bolster springs, so an adapter casting 17 is employed, said casting being notched, as indicated at 18, to fit the tension member 3^b and having an inward extension 19 to which is preferably riveted, or otherwise connected, the adjacent end of the spring plank 8^b. The adapter casting 17 is desirably secured to the frame by longitudinal bolts 20 extending through corresponding apertures in outstanding flanges 21 on the guide columns 4^b and those portions of the casting 17 disposed therebetween.

Resting on the adapter casting 17 is a nest of springs 10^b, 11^b, as in the embodiment of Figures 1 and 2, said springs, if desired, being disposed between lower and upper spring plates or caps 9^b, 12^b. In the present embodiment, a heavier plate or cap 22 is desirably placed on the upper plate or cap 12^b, and serves to directly support the bolster 13^b. Except as specifically described, the present embodiment may correspond with that of the first embodiment.

Referring now to the embodiment of my invention illustrated in Figures 7, 8 and 9, a construction is there disclosed involving a cast side frame 1^c having a compression member 2^c, a tension member 3^c, bolster guide columns 4^c, and a window opening 5^c. The tension member beneath the window opening, as in the preceding embodiment, supports an adapter casting or lower spring cap 17^c connected to the spring plank 8^c and, in the present embodiment, directly supporting a nest of helical and elliptic bolster

springs 10^c, 11^c. Although the elliptic springs may, if desired, be arranged diagonally, as in the preceding embodiment, they are, in the present embodiment, shown as disposed axially of the spring plank which is, therefore, necessarily of special construction or has the special end casting 17^c providing the necessary increased width for the purpose. 5

The bolster 13^c of the present embodiment is of the lateral-motion type and is, therefore, shown supported on rockers 23 which, in turn, engage the upper spring cap 22^c specially adapted for the purpose. The upper cap 22^c and the lower cap or adapter 17^c are, in the present embodiment, indented or provided with shoulders 15 or generally straight ribs serving to center the elliptic spring 11^c by receiving the spring bands 24. Likewise, these same members are provided with formations of a different kind, such as curved flanges or beading 25, for properly positioning or centering the coil springs 10^c.

Referring now to the embodiment of my invention illustrated in Figures 10, 11 and 12, a construction is there disclosed corresponding to Figures 7, 8 and 9, except that the frame 1^d is of the arch bar type, as in Figures 4, 5 and 6, and, therefore, has an upper arch bar member 2^d, a lower arch bar member 3^d, column members 4^d, and a tie bar 16^d, all connected by through bolts 15^d. Mounted on the lower arch bar member 3^d, as in the embodiment of Figures 4, 5 and 6, is an adapter casting 17^d connected to the spring plank 8^d and supporting a nest of helical and elliptic springs 10^d, 11^d surmounted by a spring cap 22^d and supporting lateral-motion rockers 23^d for the associated bolster 13^d. Except as specifically described in connection with the present embodiment, the same may correspond with that of Figures 7, 8 and 9. 30

From the foregoing disclosure, it will be seen 40 that I have devised an improved truck for railway vehicles in which helical and elliptic springs are employed for supporting the bolster which may, if desired, be of the lateral motion type. Although only one side frame of each embodiment has been 45 illustrated, it will be understood that the other end of the bolster is supported by a corresponding side frame, as the construction is symmetrical. The disclosure also shows how existing spring planks may be utilized by arranging the elliptic 50 springs diagonally of the associated frames, or the necessary increased width is provided by adapter castings, so that the elliptic springs may be disposed axially of the planks or transversely of the associated frames. 55

Although preferred embodiments of my invention have been illustrated, it will be understood that modifications may be made within the spirit and scope of the appended claims.

I claim:—

1. In a railway truck, in combination, a side frame having a bolster opening, a spring plank supported at one end by the side frame, a spring cap positioned in said bolster opening and movable vertically with respect to the adjacent end of the spring plank, and spring means interposed between the spring plank and the spring cap, said spring means comprising an elliptic spring bearing against said spring cap, supported by said plank, and adapted to be compressed by 65 said cap, said elliptic spring having its major axis diagonally disposed to said bolster and its opposite ends disposed on opposite sides of the side frame, and a plurality of coil springs between which said elliptic spring is positioned. 70

60

65

70

75

2. In a railway truck, in combination, a side frame having a bolster opening, a spring plank supported at one end by the side frame, a spring cap positioned in said bolster opening and movable vertically with respect to the adjacent end of the spring plank, and spring means interposed between the spring plank and the spring cap, said spring means comprising an elliptic spring bearing against said spring cap, supported by said plank, and adapted to be compressed by said cap, said elliptic spring having its major axis disposed at an oblique angle to the direction of length of the side frame and its opposite ends disposed on opposite sides of the side frame, and a plurality of coil springs bearing against said spring cap and adapted to be compressed thereby, said coil springs being spaced transversely of the side frame.

3. In a railway truck, in combination, a side frame having a bolster opening, a spring cap positioned in said bolster opening and movable vertically, and spring means interposed between that portion of the frame beneath the bolster opening and the spring cap, said spring means comprising an elliptic spring bearing against said spring cap, supported by said plank, and adapted to be compressed by said cap, said elliptic spring having its major axis diagonally disposed to said side frame and bolster, and a plurality of coil springs bearing against said spring cap and adapted to be compressed thereby, said coil springs being spaced transversely of the side frame.

4. In a railway truck, in combination, a side frame having a bolster opening, a bolster projecting into said bolster opening, and spring means positioned in the bolster opening and operatively interposed between the bolster and the side frame, said spring means including coil spring means and an elliptic spring the major axis of which forms an oblique angle with the direction of length of the side frame.

5. In a railway truck, in combination, a side frame having a bolster opening, a bolster projecting at one end into said opening, and spring means positioned in said opening and operatively interposed between the bolster and the side frame, said spring means comprising a plurality of coil springs spaced transversely of the side frame, and an elliptic spring positioned between the coil springs and having its major axis arranged at an oblique angle to a vertical plane bisecting said side frame.

6. In a railway truck, in combination, a side frame having a bolster opening, a bolster projecting at one end into said opening, and an elliptic spring operatively interposed between the bolster and side frame for yieldingly supporting the bolster, said elliptic spring having its opposite ends disposed on opposite sides of the side frame and having its major axis extending at an oblique angle to the direction of length of the side frame.

7. A spring nest adapted for insertion in the bolster opening of a railway vehicle side frame comprising an elliptic spring and a plurality of coil springs, said elliptic spring having its major axis extending at an oblique angle to the direction of length of the side frame.

8. A spring nest for insertion in the bolster opening of a railway vehicle side frame comprising a plurality of coil springs spaced transversely of the side frame and an elliptic spring extending between said coil springs, the major axis of the elliptic spring forming an oblique angle with the direction of length of the side frame and with the line connecting the centers of said coil springs.

9. A spring nest for insertion in the bolster opening of a railway vehicle side frame comprising a plurality of coil springs spaced transversely of the frame and an elliptic spring associated therewith, the major axis of said elliptic spring forming an oblique angle with a vertical plane bisecting said side frame.

10. A spring nest adapted for insertion in the bolster opening of a railway vehicle side frame and comprising an elliptic spring and a coil spring set, said coil spring set comprising a plurality of laterally spaced springs, the vertical plane of the major axis of one of said springs extending at an oblique angle to the direction of length of the side frame.

11. A spring assembly comprising upper and lower spring caps, helical springs and an elliptic spring disposed between said caps and arranged to operate in parallel under the applied load, the load surfaces of said springs contacting with the inner surfaces of said caps, and formations provided on said inner surfaces for centering the helical springs and for engaging the spring band of the elliptic spring.

12. A truck spring assembly comprising load transmitting spring caps, a plurality of helical springs and an elliptic spring located side by side between said caps, the longitudinal axis of said elliptic spring being substantially parallel to a line passing through the centers of said helical springs, and formations provided on the inner surfaces of said caps for centering the helical springs and for engaging the spring band of the elliptic spring.

13. In a railway truck side frame and in combination with a bolster, a group of springs interposed between said bolster and said frame including an elliptic spring disposed with its axis at an oblique angle to said bolster, and coil springs disposed on opposite sides of said elliptic spring.

14. In a railway truck side frame and in combination with a bolster, a group of springs interposed between said bolster and said frame including an elliptic spring disposed with its axis at an oblique angle to said bolster and with its center point substantially on the longitudinal axis of said bolster, and coil springs disposed on opposite sides of said elliptic spring.

15. In a railway truck side frame and in combination with a bolster, a group of springs interposed between said bolster and said frame including an elliptic spring disposed with its axis at an oblique angle to said bolster and with its center point substantially at the point of intersection of the longitudinal axes of said bolster and said side frame, and coil springs disposed on opposite sides of said elliptic spring.

16. In a railway truck side frame and in combination with a bolster, a group of springs interposed between said bolster and said frame including an elliptic spring disposed with its axis at an oblique angle to said bolster, and a pair of coil springs disposed symmetrically on opposite sides of said elliptic spring.

17. In a railway truck side frame and in combination with a bolster, a group of springs interposed between said bolster and said frame including an elliptic spring disposed with its axis at an oblique angle to said bolster and with its center point substantially on the longitudinal axis of said bolster, and a pair of coil springs disposed symmetrically of the longitudinal axis of said bolster.

18. In a railway truck side frame and in com-

- 5 bination with a bolster, a group of springs inter-
posed between said bolster and said frame in-
cluding an elliptic spring disposed with its axis
at an oblique angle to said bolster, and with its
center point substantially at the point of inter-
section of the longitudinal axes of said bolster
and said side frame, and a pair of coil springs
disposed symmetrically on opposite sides of said
elliptic spring.
- 10 19. A nest of springs for supporting an end of
an associated bolster comprising an elliptic
spring extending along its longitudinal axis from
one side to the other of the longitudinal plane of
an associated side frame, and coil spring means
15 on either side of said elliptic spring, the plane
joining the resultant axis of all the coil spring
means on one side with that of all the coil spring
means on the other side of the elliptic spring
being diagonally disposed with respect to said
20 longitudinal axis of the elliptic spring.
- 20 20. In a railway truck side frame, in combina-
tion with a bolster, a spring assembly interposed
between the side frame and bolster for resiliently
supporting said bolster comprising upper and
25 lower spring caps, helical springs, and an elliptic
spring disposed between said caps and arranged
to operate in parallel, the load surfaces of said
springs contacting with the inner surfaces of the
30 caps, and formations provided on said inner sur-
faces for centering the helical springs and for en-
gaging the spring band of the elliptic spring.
21. In a railway truck, in combination, a side
frame having a bolster opening, a bolster having
an end portion received in said opening, upper
and lower spring caps positioned in said bolster
opening, said upper spring cap being movable
vertically, lateral motion rocker means disposed
between said bolster and upper spring cap, heli-
cal springs and an elliptic spring interposed be-
tween said caps, the load surfaces of said springs
contacting with the inner surfaces of said caps,
10 and formations provided on said inner surfaces
for centering the helical springs and for engag-
ing spring bands of the elliptic spring. 5
22. In a railway truck, in combination, a side
frame having a bolster opening, a bolster with an
end received in said opening, upper and lower
spring caps positioned in said opening, said up-
per spring cap being adapted to move vertically
and said lower spring cap being supported by said
side frame, means disposed between said bolster
and upper cap for allowing lateral motion of the
bolster with respect to the side frame, helical
springs and an elliptic spring disposed between
said caps and arranged to operate in parallel
under an applied load, the load surfaces of said
springs contacting with the inner surfaces of said
caps, and formations provided on said inner sur-
faces for centering the helical springs and for
engaging spring bands of the elliptic spring. 20 25
